OIL CUP

Merle W. Bauman, Seattle, Wash.

Application May 10, 1938, Serial No. 207,046

1 Claim. (Cl. 308—125)

My present invention relates to oil cups and is an improvement over my copending patent application, Serial Number 163,778, filed September 14, 1937, and entitled "Lubricator." The primary objects of the present invention are to provide an oil cup that has no relatively fixed elemental points and which may therefore be connected to any and all forms and sizes of bearings. Further objects are to reduce the oil cup to its ultimate simplicity and efficiency, and to make it durable in construction, easy to replenish with oil, and which is fool proof in its use and manipulation. Still further objects are to provide novel means for securing the discharge ends of the wick 5 into a bearing, and also to provide threaded means for connecting the cup to the upper or cap member of a bearing whereby it may be set up until the bottom of the cup rests securely against the rounded top of the bearing member 10 and whereby the warmth of the bearing is communicated to the cup thus keeping the oil therein in a thinly fluid condition particularly during cold weather so that it feeds freely through the wick at all times.

25 In the drawing:

Figure 1 is a view in central longitudinal vertical section showing the oil cup connected to the upper or cap member of a bearing; and

Fig. 2 is a view in transverse vertical section taken substantially on a broken line 2—2 of Fig. 1.

Referring in detail to the drawing wherein like reference numerals indicate like parts in the several views, the numeral 5 designates the upper or cap member of a bearing which is set upon a shaft 6 that is shown in dotted lines. A standard pipe threaded hole 7 extends centrally and vertically through the bearing member to a communication with the shaft. A pair of smaller holes 8 extend upward from the shaft into the bearing, each being located near the respective ends of the bearing member. A pair of grooves 9 extend respectively from the hole 7 to the holes 8. It will be understood that the holes 7 and 8 and the grooves 9 all lie in the same vertical plane.

The oil cup comprises a cylindrical bowl 10 which has a lid 11 hinged to its top portion at 12. A relatively large central upstanding wick conduit 13 is integral with the bottom of the bowl and extends from a point a short distance below the top of the bowl to a point a short distance below its bottom. The portion of said wick conduit which extends below the bottom of the bowl is threaded at 14 to fit the threaded hole 7. One of the important features of the invention

resides in the fact that said depending portion of the wick conduit is threaded all the way to the bottom of the bowl or in such other manner that it may be screwed down so that the bottom of the bowl engages against the top of the bearing 5. This feature is important for the reason that the frictional heat that is created in the bearing member 5 by the rotating shaft 6 is readily communicated to the bowl 10 and keeps the oil 15 therein in a thinner or more fluid condition so that it flows freely through the wick 16 at all times.

In the assembly and use of the device, assuming that the bowl 10 is threadedly connected to the bearing member 5 as shown in the drawing, the wick 16 is threaded through the upstanding conduit 13 with several inches projecting both above and below same. The depending part of the wick is then separated into two substantially equal portions 17, and each respective portion is fitted into the two grooves 9 extending in opposite directions from the central hole 7. The respective ends of said wick portions are inserted into the small holes 8, and small wooden pegs or wedges 18 are forced into said holes for the purpose of securing said ends therein as will be understood. The upper portion of the wick is laid down into the bowl which is then filled with the oil 15 to a point slightly below the upper end of the conduit 13.

Making the conduit 13 of unusually large diameter in cross section is a very important point in this invention. In so doing, the body of the wick 16 is made to comprise an abnormally large number of strands of standard wicking and sufficient to fill the conduit without any jamming. Furthermore, when this wick is separated into the two equal parts 17 there is sufficient wicking in each part to completely fill the grooves and to bulge slightly outside of same, as shown in Fig. 2, and thus ensure contact with the shaft 6. Moreover, it has been discovered that, after this wick has become thoroughly saturated with oil, its strands may be clipped off, a few at a time, at the top of the conduit, as shown at 19 in Fig. 1, until only several remain as feeders for the oil. In fact it has been found that only two strands are sufficient to supply oil to the body of the wick for a bearing and shaft of considerable size. A test extending over a period of approximately 50 a year has shown that an oil cup made in accordance with the foregoing description resulted in a saving of two-thirds of the oil used in the cup which it displaced, and with no burnt out bearings or shaft trouble whatever. This saving 55

in oil results from the fact that the shaft 6 takes oil from the cup 10 through the wick 16 by attractive absorption only at times when it is needed by the shaft and in the correct amount 5 that is needed, without any loss. This cup may be installed on any bearing of normal size for the reason that it has no elements of fixed relation, the threaded hole 7 may be at any point in the top of a bearing, and the plug-in holes 8 may 10 be placed at any desired distance from the hole 7, depending upon the length of the bearing on which the cup is to be installed. Placing the small holes 8 close to the ends of the bearing supplies sufficient lubricant for its ends without 15 waste of the oil.

I claim:

The combination with the upper or cap member of a bearing having a large hole threaded downward therethrough, a pair of smaller holes each 20 extending upward into the bearing a short distance from its respective ends, and a pair of

grooves extending respectively from the large hole to each of the smaller holes, of an oil cup comprising a bowl, a large wick conduit extending from a point a short distance below the top of the bowl to a point a short distance below its 5 bottom, the depending portion of said conduit threaded all the way to the bottom of the bowl, said depending conduit portion threaded all the way into the hole through the bearing member with the bottom of the bowl engaging the top of 10 said bearing member, a large wick passing from the bowl downward through the conduit and outward through the large hole in the bearing, said outwardly extending portion of the wick separated into two substantially equal parts with 15 each part extending along the aforesaid grooves and having their respective ends inserted into the aforesaid smaller holes, and pegs forced into said smaller holes for securing said ends therein.

MERLE W. BAUMAN. 20
